APPARATUS FOR AND METHOD OF APPLY-
ING CIGAR BANDS

Ernst Hermann Jähne, Dresden, Germany, assignor, by mesne assignments, to J. C. Muller N. V., Rotterdam, Netherlands

Application September 8, 1937, Serial No. 162,845
In Germany September 22, 1936

13 Claims. (Cl. 131—106)

The present invention relates to a method and device for applying superimposed bands on cigars. It is frequently desired to place two or more bands upon a cigar. The presence of a band indicating that a tax has been paid is frequently required by law. The identifying ornamental band is usually desired by the manufacturer. A portion of the tax band, which is a narrow band as a rule, must be visible on the cigar so that if the ornamental band be superimposed upon the tax band one must be displaced from the other so that one edge of the tax band will be visible.

Formerly banding with two different bands was accomplished by having the band applying device operate with two magazines of bands, the device drawing a band from one magazine and applying it and then being shifted to draw a band from the second magazine and applying it over the first. Such a device is not only complicated in construction and delicate because of the various motions it must have, but it is slow. A single cigar must remain in the region of the banding device while the device performs two operations.

A considerably more rapid and satisfactory method of banding with two different bands is to employ two banding devices of similar construction and move the cigars successively past them. One of the devices applies the first band and the second applies the second band.

The present invention has for its object to provide means whereby two similarly constructed banding devices may be used to apply two bands in partly overlapping relation.

Another object is to provide means in which two bands of different widths may be applied in the desired relation on a cigar.

A further object is to provide a continuous banding device to accomplish the above named objects.

Another object is to provide a method of operation for use in applying two or more superimposed bands on a cigar in partly overlapped relation.

In general the invention is carried out by moving the cigar past two similar banding devices and effecting, after the first band has been applied, an axial displacement between the cigar and the second banding device. In one form of construction this effect is produced by having the second banding device of a shorter amplitude of movement than the first whereby the second band is placed nearer to the end of the cigar than the first by an amount sufficient so that

a portion of the underlying band will remain visible after the upper band is applied.

Another construction to accomplish the purpose consists in locating one of the banding devices closer to the path of the moving cigars than the other whereby the same amplitude of movement places the bands in different positions on the cigar. A third type of construction involves the displacement of the cigar itself after it leaves the first banding device.

With the foregoing and other objects in view, the invention will be more fully described hereinafter, and will be more particularly pointed out in the claims appended hereto.

In the drawings, like symbols refer to like or corresponding parts throughout the several views.

Figure 1 is a plan view of a device embodying the first form of construction.

Figure 2 is a vertical section taken on the line II—II of Figure 1.

Figure 3 is a plan view of a device embodying the second form of construction.

Figure 4 is a vertical section taken on the line IV—IV of Figure 3.

Figure 5 is a plan view of a device embodying the third form of construction, and

Figure 6 is a vertical section taken on the line VI—VI of Figure 5.

Referring now to Figures 1 and 2, 2 represents a work table which is provided along its length with a pair of slots 2' in which operates an intermittent conveyor 1 which has troughs or cradles 3 at spaced points to receive cigars Z. This conveyor is driven in any of a number of well known manners to produce a step by step advance of the cigars along the table in the direction of the arrow in Figure 1. The cigars Z are held in line by means of a guide 8 which runs parallel to the conveyor 1. At spaced points along the conveyor 1 the band applying devices 4 and 5 are located.

These devices are shown in dotted lines in Figures 1 and 2 and are of well understood construction. For instance the band applying devices may be of the type shown in the patent to Malocsay No. 1,261,831. It will be noted from Figure 1, that the band applying device 5 is nearer to the left run of the conveyor 1 than is the band applying device 4. Opposite the device 4 is a feeding head 4' which, as is well known, is constructed of hollow arms connected at one end with a vacuum pump and open at the other end, as for instance, is shown in the Malocsay Patent No. 1,261,831. The ends of the head 4', nearest to the conveyor 1, are upturned and open. The 45

head 4' is carried by a bracket 20 which is secured pivotally to the top of an arm 21. The bracket 20 is likewise pivotally secured to the top of an arm 22 which as shown is of adjustable length. 5 The arm 21 is pivotally secured to a shaft 23 running lengthwise beneath the table 2. This arm 21 moves the bracket 20 and head 4' into and out of the path of the cigars. The required motion is produced by the rotation of a shaft 24 10 carrying a cam disc 25 against which bears a roller 26 on the arm 21. The roller 26 is yieldably pressed against the edge of the disc 25 by means of a spring 27 secured at one end to the arm 21 and at its outer end to the bracket 28 fastened to the table 2. As the shaft 24 is rotated the arm 21 swings about the shaft 23 and advances the head 4' to a position beneath the banding device 4. The head 4' is rocked in a vertical sense by means of the adjustable arm 22 15 which is pivotally secured at its lower end to a yoke 29 pivoted on the shaft 23 and carrying at its opposite side a short arm 30 which carries a roller 31. A smaller cam disc 32 fixed to the shaft 24 provides the motion for the arm 30 and the adjustable arm 22. The roller 31 is retained against the edge of the disc 32 by means of the spring 33 fastened at one end to the short arm 30 20 and at its opposite end to the table 2. It will be seen that in the position shown in Figure 2 the roller 31 is riding on the highest point of the disc 32 and the head 4' is in its uppermost position against the bottom of the stack of bands Zu' which are held in the magazine 6. This magazine, as is well known, is open at the bottom and 25 the open upper ends of the head 4' are applied against the surface of the lowermost band Zu'. For example of the details of this structure see Malocsay Patent No. 1,261,831. The suction in the head 4' is sufficient to pull this lower band 30 away from the stack when the head 4' is moved downwardly as the roller 31 rides down on a lower portion of the cam disc 32. The band Zu' is then carried with the head 4' out beneath the applying device 4 which wraps it and secures it 35 about the cigar Z.

The band applying device 5 has located opposite it a feeding head 5' of identical structure with the head 4'. The head 5' moves in the direction of the cigars a shorter distance than 40 the head 4'. The amplitude of movement of the head 4' is indicated by the length line marked X in Figure 1 while the amplitude of the head 5' is indicated by the length line Y. The shortening of the stroke of the head 5' is accomplished by 45 reducing the maximum diameter of the cam disc corresponding to the disc 25 associated with the head 4'. Such a reduction in diameter is indicated in dotted lines in Figure 2.

The movement of the conveyor 1 and the operation of the heads 4' and 5' and of the band applying devices 4 and 5 is timed so that a cigar is placed in front of each of the devices and stopped long enough for the devices to perform their operations and then the conveyor moves 50 sufficiently to place a subsequent cigar opposite each of the devices. Such synchronous operation of the conveyor, the band feeding, and the band applying units is well-known in the art and may be accomplished by adopting a driving mechanism such as shown in the U. S. patent to Schmiedel No. 2,065,029. The structure above-referred to 55 forms no part of this invention or the claims directed thereto. In this way, the operation of the banding machine is constant and the second band is being applied to one cigar as the first is

being applied to another; thus, only the time of a single banding operation is consumed. In the drawings the first band, usually the tax band, is indicated by Zu' and held in the magazine 6. The second band Zu'' is the ornamental or identifying band and is held in the magazine 7. The ornamental band Zu'' is placed nearer to the round end of the cigar than the tax band by an amount sufficient to leave a substantial portion of the tax band visible. The magazines 6 and 7 and the feeding heads 4' and 5' are placed on the table 2 in line with one another, that is, they are spaced equal distances from the conveyor 1. The only difference in the devices is that the band applying device 5 is nearer the left hand run 10 of the conveyor 1 than is the band applying device 4 and the stroke of the feeding head 5' is shorter as explained.

Figures 3 and 4 illustrate the second form of construction. In this construction identical band 20 feeding heads 4' and 5' are used. The stroke of each also is the same, the cam disc of the feeding devices being identical. The variation in the position at which the band is applied is obtained by locating the entire feeding head assembly 4' 25 nearer to the left run of the conveyor 1 than the feeding head assembly 5'. The band applying devices 4 and 5 are located as in the previously described form of construction shown in Figures 1 and 2. Figure 4 shows clearly the lateral displacement of the magazines 6 and 7, the magazine 7 being further away from the ends of the cigars than the magazine 6. The result of this construction is that the same magnitude of stroke in the two feeding heads 4' and 5' produces different 30 positionings of the bands Zu' and Zu'' upon the cigar.

Referring now particularly to the third form of construction as shown in Figures 5 and 6, the band applying devices 4 and 5 are shown directly 40 in line with regard to the conveyor 1. The feeding heads 4' and 5' together with their respective magazines 6 and 7 are likewise located in the same longitudinal line on the table 2. In this construction the cigar itself is moved before the 45 second band is applied. The cigars are held in line at the end of the table 2 adjacent the band applying device 4 by means of a short guide rail 17 which ends somewhere between the first and second band applying devices. After the end of 50 the guide rail 17 another short guide 18 is located on the table at a point further removed from the conveyor 1. Opposite a portion of the guide 18 a pusher 9 is located and synchronized with the conveyor and the band applying device 55 so that when the cigars stop it pushes one of them against the guide 18 thus shifting it lengthwise before it arrives opposite the second banding device 5. As shown in Figure 6 the pusher 9 is composed of a rod 9' slidably mounted in a pair 60 of spaced blocks 10. The end of the rod 9' opposite the cigars extends over the edge of the table 2 and carries a pin 34 at one side. A bell crank lever 11 is pivotally mounted on the table 2 by means of the pivot 12. At its upper end the lever 65 11 carries a yoke 35 which fits around the pin 34 and transmits the motion of the lever thereto. At its lower end the lever 11 carries a roller 13 which plays against the edge of a cam disc 36 and against which edge it is held by means of the 70 traction spring 14 attached at one end to the lower arm of lever 11 and at the other end to a portion of the table 2. The disc 36 is mounted on the shaft 24 with the discs controlling the feeding heads 4' and 5' and rotates with them. 75

At the same time that the feeding heads advance a band over a cigar the pusher 9 advances against the end of a cigar adjacent to it and shifts it by an amount sufficient to place it against the 5 guide 18. The amount of this movement is sufficient to produce the desired displacement of the second band Zu' away from the first band Zu'.

The invention above described is not limited, of course, to the particular bands applied but the 10 need for spacing the tax band and the ornamental band of a cigar forms one useful purpose to which the invention may be applied. In its broader sense the invention consists in employing banding devices of the same type at spaced 15 points. The cigar is moved past the banding devices and some time before the first and the second of said devices a shift lengthwise of the cigar is produced between the position of the first band and that of the second.

20 It is obvious that various changes and modifications may be made in the details of construction and design of the above specifically described embodiment of this invention without departing from the spirit thereof, such changes and modifications being restricted only by the scope of 25 the following claims.

What is claimed is:

1. A device for applying bands on cigars comprising a pair of spaced means for placing a 30 band on a cigar, means for moving a cigar successively past each of said first named means, and means for moving the cigar to change the relative position between the cigar and the second of said first named means to displace the second band lengthwise of the cigar from the first.

2. A device for applying bands on cigars comprising a band applying means, a conveyor to carry the cigar past said means, a second band 40 applying means similar to the first disposed in spaced relation to the said first means along the path of said conveyor and located a different distance from the conveyor than said first means whereby said second means places the second 45 band at a different place on the cigar from the first band.

3. A device for applying bands on cigars comprising a band applying device, a reciprocable band feeder for said device, a second band applying device, a reciprocable band feeder for said 50 second device, and a conveyor for moving a cigar successively past said devices, said second band applying device being located at a point removed with regard to the conveyor by an amount different than the first named device, and the feeder for said second device having an amplitude of reciprocation different than the feeder for the first named device to deliver a band to said second device, whereby the band applied by the second device is at least partly displaced with regards to 55 the band applied by the first named device.

4. A device for applying bands on cigars comprising an intermittent conveyor for carrying a cigar crosswise along a path, a band applying device located above said conveyor at a position corresponding to the desired band position on a cigar, a reciprocable feeder for said device to deliver a band thereto, a second band applying device along the path of said conveyor and located above said conveyor at a position laterally removed from the first device, and a second reciprocable feeder for said second device to deliver a band to said second device whereby the bands applied by the devices are partly displaced from 60 one another.

5. A device for applying bands on cigars comprising an intermittent conveyor for carrying a cigar crosswise along a path, a band applying device located above said conveyor at a position corresponding to the desired band position on a 5 cigar, a reciprocable feeder for said device to deliver a band thereto, a second band applying device along the path of said conveyor and located above said conveyor at a position laterally removed from the first device, and a second reciprocable feeder located the same distance from the 10 said conveyor as the first named feeder and having its amplitude of movement different from said first named feeder to deliver a band to said second device, whereby the bands applied are 15 partly displaced from one another.

6. A device for applying bands on cigars comprising a conveyor for carrying a cigar crosswise along a path, spaced band applying devices located above said conveyor in a line parallel to 20 said path, and means for moving a cigar laterally on the conveyor after it leaves one of said devices and before it reaches the next of said devices whereby the band applied by the succeeding device is displaced along the cigar from the preceding band.

7. A device for applying bands on cigars comprising a conveyor for carrying a cigar crosswise along a path, spaced band applying devices located above said conveyor in a line parallel to 30 said path, a cigar guide along said conveyor opposite each of said devices, the guide opposite succeeding devices being laterally spaced from the conveyor by an amount different than a preceding guide, and means between said band applying devices for moving a cigar from its position against one guide to a position against the succeeding guide, whereby the bands applied by successive devices are displaced from one another.

8. A device for applying bands on cigars comprising a conveyor for carrying a cigar crosswise along a path, spaced band applying devices located above said conveyor in a line parallel to 40 said path, a cigar guide along said conveyor opposite each of said devices, the guide opposite succeeding devices being laterally spaced from the conveyor by an amount different than a preceding guide, and a pusher beside the conveyor between the band applying devices to engage the end of a cigar and move it lengthwise from one 45 guide position to the succeeding one.

9. A device for applying bands on cigars comprising a pair of spaced band applying devices, an intermittently moving pusher between said devices, an intermittent conveyor for moving a 55 cigar crosswise along a path and stopping it opposite one of said band applying devices then opposite said pusher and then opposite the second of said band applying devices whereby the cigar is moved lengthwise before it arrives opposite the 60 second band applying device, and a guide for said cigar extending beside said conveyor and having the part opposite the pusher and said second device set back from said conveyor more than the part opposite the first of the band applying devices, said pusher adapted to move the cigar against the set back part of said guide.

10. A method for applying a plurality of superimposed bands upon a cigar which comprises moving the cigar to a first band applying position, then advancing the cigar to a second band applying position, and effecting a relative displacement lengthwise of the cigar between said second band applying position and the cigar before said cigar arrives at said second band apply- 70 75

ing position whereby the band applied at said second position is displaced from the band applied at said first position.

11. The herein described method for applying 5 tax and manufacturers' bands to cigars in which the cigars are carried along on a conveyor which is intermittently moved, which consists in applying at one station the tax band to a cigar on the conveyor during an interval of stoppage of the 10 conveyor, advancing the banded cigar to a subsequent station, and applying a manufacturers' band in partially offset and partially overlapping relation with respect to the tax band at such subsequent station during a subsequent stoppage 15 interval of the conveyor, and at the same time interval period as said manufacturers' band is applied at the second station applying at the first station a tax band to a later cigar in the sequence of cigars on the conveyor whereby the steps of 20 applying both the tax and the manufacturers' bands to the cigars, while taking place in subsequent time periods of stoppage of the conveyor occur simultaneously as to operative action and such operative action at both stations occurs 25 within the same time interval period of stoppage of the conveyor.
12. An apparatus of the kind described comprising an intermittently moving conveyor having means spaced along its length at stated intervals for receiving cigars, a plurality of band applying stations spaced along the length of the conveyor and located in positions opposite to the cigar holding means of the conveyor when stopped whereby cigars on the conveyor will be in 30 band applying position with respect to all said stations when the motion of the conveyor is ar-

rested, means at an initial station for applying a tax band substantially completely around the cigar resting at that station, means at a subsequent station for applying a manufacturers' band substantially about the cigar and in the partially offset and partially overlapped relation with respect to said tax band whereby the band applying means at all the stations may operate substantially simultaneously and within the same minimum time interval of stoppage of the conveyor 10 to the end that the double banding may be achieved in a time interval of conveyor stoppage no longer than that required for the application of a single band.

13. An apparatus of the kind described comprising 15 an intermittently moving conveyor having cigar holding means thereon at stated intervals, a plurality of band applying stations located along the length of said conveyor and positioned relatively to the conveyor and to the cigars thereon whereby at each stoppage of the conveyor cigars will be brought opposite each of said stations in band applying position, band-applying means at an initial station for applying a band substantially circularly about the cigar resting at 20 such station, band-applying means at a subsequent station associated for simultaneous operation with the band-applying means at the initial station for applying a second band substantially circularly about the cigar, and means for relatively setting the cigars and said band-applying means whereby the second applied band will be partially offset and partially overlapped with the first applied band.
